UNITED STATES PATENT OFFICE

JOHN F. GAIL, OF EVANSTON, ILLINOIS, ASSIGNOR TO SIMMONS COMPANY, OF NEW YORK, N. Y., A CORPORATION OF DELAWARE

GANG SEWING APPARATUS

Application filed August 12, 1925, Serial No. 49,684. Renewed June 19, 1929.

My invention relates to improvements in gang sewing apparatus, and is of especial value in connection with the sewing of the transversely extending pocket defining stitch lines of strips of fabric used in the construction of cushions or mattresses of the well-known Marshall type.

The principal object of the invention is to produce an improved, simple, economic, 10 efficient and rugged apparatus for the purpose described.

In the drawings accompanying this application, and illustrating a specific application of my invention,

15 Fig. 1 is an end view, partly in section of a gang sewing machine embodying my invention.

Fig. 2 is a section taken on the line 2—2 of Fig. 1.

20 Fig. 3 is a plan view of the machine and Fig. 4 is a section taken on the line 4—4 of Fig. 2.

Referring to the drawings it will be seen that the machine in its main elements comprises a row of stitching-heads extending across a series of supporters or carriers by which the work is conducted through the field of the stitching-heads. In view of the fact that stitching-heads of the gang type 25 are not new in the art, I have not illustrated in the drawings, nor shall I describe all of the details thereof. It will be enough to indicate the needlebar 10, the presser 11 and the lower feed-plate 12 of each of the 30 heads, without describing their associated instrumentalities by which the work is fed through the machine and stitched.

The stitching-heads as to their upper mechanisms, are mounted in a horizontally 40 extending hollow girder-like casting 13 which at its ends is supported by suitable end frames 14 and 15. The lower parts of the feed and stitching mechanisms are mounted in a similarly extending lower casting 16, said casting being provided with flange-like side extensions 17 and 18, which, together with the upper portion of the casting 16 constitute a work-table. The said work-table is as to its upper surface, grooved 45 out in between the stitching-heads in order

to form supports or run-ways for a series of work-supporting and propelling chains 19. The upper stretch of each of said chains slides in one of the said table-grooves and the lower stretch of the said chain extends under 55 the girder member 16.

The work receiving ends of said chains 19 are trained around sprocket-wheels 20 which are mounted on a common shaft 21 supported between floor standards or brackets 22 and 23. The delivery ends of said chains are trained around similar sprocket-wheels 24, all of which are keyed to a common shaft 25, supported to rotate in the bearings of spaced brackets or floor standards 26 and 27. Said chains thus may all be driven by rotating shaft 25.

The needle-bar and other mechanisms in the upper cross-frame or girder 13 are actuated by a series of beveled gears 28 and 29 respectively mounted on the individual cross shafts 30 of each stitching-head, and the horizontal or transversely extending main shaft 31 which is common to all of the stitching-heads. The operating parts of the 75 feed and stitching mechanisms below the work are all driven by a single horizontal transversely extending shaft 32. The two shafts 31 and 32 are caused to rotate in unison with each other, by means of spur 80 gears 33 and 34 keyed respectively to the shafts 31 and 32, and each having an equal number of teeth therein. The shaft 31 is continuously driven by a pulley 35 keyed to said shaft and operated by a constantly 85 running belt 36. As seen best from inspection of Figs. 1 and 3, there is keyed to the outwardly projecting end of the main bar shaft 31 a worm 37 which meshes with a worm gear 38, keyed to a side horizontal 90 shaft 39, one end of said shaft being supported in suitable bearings formed as parts of the gear housing 40. The opposite end of said shaft 39 is supported to rotate in bearings formed in a worm-gear housing 95 41 formed on the side of the standard 27.

The worm 42 which is keyed to the shaft 39, meshes with a second worm-gear 43 contained in said worm-gear housing 41 and keyed to the end of the shaft 25, so that 100

when the main shaft 31 of the stitching mechanism is continuously operated, the chains 19 will also move continuously through the field of the stitching mechanisms, but at a greatly reduced speed.

It will be understood that there are sufficient stitching-heads and the main side frames are spaced widely enough apart to accommodate the longest strip of pockets for which the machine is required. For instance, if it is desired to sew a strip which is to contain fourteen pockets, it will be necessary to employ fifteen stitching-heads spaced apart a distance equal to the width 10 of the pocket before the springs are inserted.

Although in some embodiments of the invention the strips might be fed to the gang of stitching-heads by hand, I find it desirable to employ some positive or more reliable method of presenting the work to the stitching-heads, the chains above described constituting one form of such a propelling mechanism. The advantages of a positive propelling mechanism are particularly apparent when dealing with a strip having a large number of pockets to be sewn therein and where the stitching-heads are operated continuously and at high speed for economical production. The use of the positive 20 propulsion mechanism has another advantage. For instance, in cases where it is desired to avoid the expense and labor of clipping the lines of stitching which connect successive strips, it is advantageous to clip 25 or sever said lines of stitching automatically as the completed strips are delivered from the stitchers. Such automatic severing is made much easier by synchronizing the severing mechanism with the feeding mechanism. 30 To this end the chains are driven in unison with the stitching-heads as heretofore described.

In order to present the edge of the strip properly to the feeding mechanism of the 45 stitching-heads, the strips of fabric when laid over the conveyor chains at the work receiving end of the machine should preferably be secured to the chains at the front edges of the strips with some degree of pos- 50 sitioning and the strip should be held fairly taut, that is to say, there preferably should not be any wrinkles or folds present in the length of the strip. In order to effect this, I prefer to secure to the chains at properly 55 spaced intervals, small forwardly extending needle points 44 with which the front edge of the fabric or strip may be manually engaged by the person placing the strips on the feed chains. The rows of points 44 are 60 preferably spaced apart a distance greater than the width of the strip so that there will be sufficient space between the strips to permit the free operation of the severing mechanism which will later be described.

65 I also find it desirable to support the strip

intermediate the chains at the work receiving end of the machine. Said support may consist of a board or platform 45, the upper surface of which is grooved out to admit and form a run-way for the chains 19. Preferably the front edge of the board 45 is slightly above the edge of the metal work-table or flange 17, so that the edge of the fabric will not catch, even though it has a tendency to hang down somewhat between the adjacent chains. It will be understood that as soon as the chains carry the front edge of the strip within range of the stitching-head feed mechanisms, control of the feed of the strip is then assumed by the stitching-head feed mechanism.

The severing mechanism comprises a series of electrically operated mechanisms, each of which is aligned with its associated stitching head. As shown best in Figs. 2 and 4, each of said severing mechanisms comprises an upper knife or shear member 46 which cooperates with a lower shear member 47. All of the lower shear members 47 are carried by a girder or angle iron member 48, the ends of which are bolted to the main frames 14 and 15 respectively. The upper or movable knife 46 is secured to the lower end of the vertical rod 49, preferably of brass and at its upper end secured in the plunger 50 of a solenoid having a winding 51. The winding of the solenoid is carried by a tube or sleeve 52 supported between the iron-heads or end-plates 53 and 54 of the solenoid. The return circuit of said solenoid is obtained through the body of the transversely extending casting 55 by which the solenoids are secured to the main cross-frame 13.

The upper end of the solenoid plunger 50 is extended upwardly through the head 53 a sufficient distance to accommodate the coiled compression spring 56 which is interposed between the head 53 and a crown or plate 57 secured to the upper end of the said plunger 50 so that after the solenoid winding has been momentarily energized the spring 56 will elevate the plunger back into its normal position as shown in Fig. 2.

The windings of the solenoid are all simultaneously energized by means of a common source of electric current, for example, a battery 58, the circuit of which is controlled by and passes through a single pair of contacts 59 and 60 mounted on a small upwardly extending fixed bracket 61. Said contacts 59 and 60 are brought together momentarily by means of a rock lever 62 mounted on a pivot 63 also carried by bracket 61. The lower end 64 of said lever 62 is adapted to extend into the path of a series of pins as at 65, projecting latterly from the side of the outside chain 19, there being one of such pins 65 for each row of points 44 and said pins being so spaced that 130

the severing plungers will be operated just after the rear edge of the strip has passed under the cutter.

The described details of construction and operation being illustrative of only one phase of my invention, the scope of which should be determined by reference to the appended claims, said claims being construed as broadly as possible, consistently with the state of the art.

I claim as my invention:

1. In a gang stitching machine of the character described, the combination of a row of vertically operating stitching heads and means for supporting and driving the same, a work table beneath said stitcher heads formed with transverse grooves in its upper surface substantially midway between said stitcher heads, a platform at the work receiving end of the machine registering at its inner edge with one edge of said work table and slightly higher than the latter, said platform formed with transverse grooves in its upper surface registering with the grooves of said work table, a group of conveyor chains disposed with their upper laps traveling through said grooves, pins on said conveyor chains operative to impale and advance the work over said platform and work table, and means for driving said conveyor chains and stitching heads in a fixed speed ratio to each other.

2. In a gang stitching machine of the character described, the combination of a row of vertically operating stitching heads and means for supporting and driving the same, a work table beneath said stitcher heads formed with transverse grooves in its upper surface substantially midway between said stitcher heads, a platform at the work receiving end of the machine registering at its inner edge with one edge of said work table and slightly higher than the latter, said platform formed with transverse grooves in its upper surface registering with the grooves of said work table, a group of conveyor chains disposed with their upper laps traveling through said grooves, pins on said conveyor chains operative to impale and advance the work over said platform and work table, a row of thread cutters located beyond said stitcher heads with reference to the direction of travel of the stock, springs normally holding said thread cutters idle, magnets for effecting working strokes of said thread cutters, a normally open circuit including said magnets and a circuit closer, and means on one of said conveyor chains for actuating said circuit closer at uniform intervals.

3. In a machine for sewing textile fabric strips along spaced transversely extending lines, the combination of a conveyor adapted to support and hold a series of said strips at spaced points along the length thereof

and to propel them unidirectionally, bodily, and successively sidewise into and through a stitching zone, a series of like sewing mechanisms similarly positioned and aligned in spaced relation across the stitching zone and arranged to operate upon said strips at a series of spaced points along the length of the strips during the movement of the latter, each of said sewing mechanisms comprising a needle and a presser foot on one side of the path of movement of the strips, and a feed plate on the other side of said path, means for actuating said parts of the sewing mechanisms in synchronism, and means for actuating said conveyor.
